UNITED STATES PATENT OFFICE.

ARTHUR T. GREENOUGH AND WILLIAM H. BOARDMAN, OF FRANKLIN, NEW JERSEY, ASSIGNORS TO ANDREW PECK AND W. IRVING SNYDER, BOTH OF NEW YORK, N. Y.

TENNIS-RACQUET.

SPECIFICATION forming part of Letters Patent No. 293,573, dated February 12, 1884.

Application filed December 19, 1883. (No model.)

To all whom it may concern:

Be it known that we, ARTHUR T. GREENOUGH and WILLIAM H. BOARDMAN, both of Franklin, in the county of Essex and State of New Jersey, have made certain new and useful Improvements in Lawn-Tennis Racquets, not heretofore known or used; and we hereby declare the following to be a full and clear description of the same, reference being had to the accompanying drawings, in which—

Figure 1 is a face view of the entire racquet. Fig. 2 is a section of a portion of the bowl with a tennis-ball resting thereon. Fig. 3 is a section of the handle of the racquet at *xx*, Fig. 1; 15 and Fig. 4 is a section of the rim of the bowl.

Our invention relates to the construction of the bowl of what is known as a "lawn-tennis racquet" and the shaping of the rim surrounding the strings, the object being to obtain the most available and serviceable face or string-surface which is interfered with as little as possible by the surrounding rim, while at the same time there may be such a distribution of weight between the bowl and handle as to produce a proper balance of the whole racquet.

In the drawings, A is the handle of the racquet, and B is the bowl or head, which forms the batting-surface, usually constructed of strings of gut crossing each other and passing 30 through a surrounding rim, C.

In the construction of tennis-racquets it is necessary that the rim C, forming the outer portion of the bowl, should have great strength, so as to bear sudden strains, and that the bowl 35 should be of such form and construction that it will bear the tension of the strings and keep them taut without losing shape. In order to retain this required strength of rim in the racquets heretofore manufactured, very little of the wood of the rim has been cut away, and the 45 rim has been made with the inner side either square, as on the outer edges, or slightly rounded, as shown by the dotted lines at *a* in Fig. 2. We have found by experiment that such a formation of rim materially interferes with the construction of a good racquet, as the weight of wood in the rim requires a corresponding weight in the handle, in order that the whole racquet shall be well balanced, thereby mak-

ing it necessary to have a comparatively very heavy racquet if the bowl or batting-surface be above a medium size. The rim on the inside, being at right angles with the stringed surface, has also been found to interfere with the tennis-ball when it strikes near the edge of the bowl, as the ball, when it impinges against such a rim, will not rebound in the direction intended. In order to overcome these defects, we have constructed the bowl with the inner edge of the rim C chamfered or cutaway, as shown in Figs. 2 and 4, so that the ball, when striking near the edge of the bowl B, will not be interfered with by the rim, and the rim being lightened by the cutting away of its inner edge, the bowl may be made much larger and of better shape with the same weight of wood as the old form of rim would require.

In forming the inner side of the rim C it may be made slightly concave, as shown in dotted lines, Fig. 4, if desired, instead of a straight bevel, both for the purpose of still further lightening the bowl and presenting a better surface for the ball when it strikes near the edge, the strength of the rim not being materially effected even when the wood is reduced by a slightly concave form at this point. In the construction of this class of racquet the bowls have been made in various forms, all of an irregular shape and without reference to any mathematical principle of construction.

By experiment we have discovered that the most available batting-surface is obtained by having the sides of the bowl follow substantially imaginary lines (as shown by dotted lines *b*, Fig. 1) drawn from a point at the center of the end of the handle of the racquet to the base of the bowl, the lines diverging equally from the center of the handle. In order, however, to furnish the rim C of the bowl with sufficient spring to keep the stringing taut, it is necessary that its sides and base should be slightly bowed, instead of on a straight line, as will appear in Fig. 1. The handle is nearly square in form, with the corners slightly rounded, as shown in Fig. 3.

What we claim as our invention, and desire to secure by Letters Patent, is—

1. A tennis-racquet having a strung bowl,

B, formed by a rim, C, shaped so that its sides will follow substantially lines which diverge equally from the center line of the handle and meet at the center of the end of the handle, as shown in Fig. 1, as and for the purposes shown and described.

2. A tennis-racquet or bat with rim C beveled or chamfered on the inner face surrounding the strings, substantially as shown and described.

3. A tennis-racquet with rim C chamfered or beveled on the inner edge, so that the plane of the chamfer or bevel is substantially tangent to the surface of a ball which touches the surface of the stringed portion and the rim at the same time, as and for the purpose shown and described.

4. In a tennis-racquet or bat, the chamfered or beveled rim C, formed and shaped to form a bowl to receive strings, as shown in Fig. 1, in combination with a handle, A, substantially as shown and described.

5. In a tennis-racquet, the rim C, with its inner edge cut away so as to form a concave bevel from the strings to the face of the rim, substantially as shown and described.

ARTHUR T. GREENOUGH.

WM. H. BOARDMAN.
